UNITED STATES PATENT OFFICE.

LOUISE A. WALLIS, OF LOS ANGELES, CALIFORNIA.

DESIGN FOR A DOLL.

Application filed November 16, 1922. Serial No. 4,313. Term of patent 14 years.

To all whom it may concern:

Be it known that I, LOUISE A. WALLIS, a citizen of the United States, residing at Los Angeles, county of Los Angeles, State of California, have invented a new, original, and ornamental Design for Dolls, of which the following is a specification, reference being had to the accompanying drawing, forming part thereof.

The figure is a front view of a doll showing my new design.

I claim:

The ornamental design for a doll, as shown.

LOUISE A. WALLIS.
